UNITED STATES PATENT OFFICE.

WILLIAM S. GUNN, OF GRAND RAPIDS, MICHIGAN.

FOLDING BED.

SPECIFICATION forming part of Letters Patent No. 469,518, dated February 23, 1892.

Application filed May 25, 1891. Serial No. 394,018. (No model.)

To all whom it may concern:

Be it known that I, WILLIAM S. GUNN, a citizen of the United States, residing at Grand Rapids, in the county of Kent and State of Michigan, have invented certain new and useful Improvements in Folding Beds; and I do hereby declare the following to be a full, clear, and exact description of the invention, such as will enable others skilled in the art to which it appertains to make and use the same.

My invention relates generally to folding beds, and particularly to a folding bed in combination with a "hall-tree" or hat-rack and to improvements in connection therewith whereby the bed may be lowered for use or raised into the frame of the hall-tree and concealed from view when not in use; also, it relates to other improvements hereinafter specified; and it consists in the novel constructions and arrangements or combinations of parts hereinafter disclosed in the description, drawings, and claims.

The objects of my invention are, first, to provide a light and compact article of furniture in which the bed-frame can be lowered or raised conveniently by an easy movement; second, to provide a novel arrangement of parts for swinging the folding bed-frame into the casing of the hall-tree; third, to provide for balancing the bed-frame while it is being raised or lowered, so that it will not close suddenly, but can be slowly closed by a slight pressure, and, fourth, to dispense with the heavy weights usually employed in this class of beds, as more fully explained hereinafter. These objects are accomplished by the improvements illustrated in the accompanying drawings, forming part of this specification, in which the same reference-numerals indicate the same parts, and in which—

Figure 1 represents a perspective view showing the rear of the hall-tree casing and the bed-frame detached therefrom with the pillow-board in the position which it assumes when the bed is closed or folded in the casing; Fig. 2, a perspective view showing the front of the hall-tree or rack and the bed-frame partly lowered, and Fig. 3 a perspective view showing the rear of the casing with the bed-frame down and the pillow-board unfolded ready for use.

In the drawings the numeral 1 indicates

the bed-casing which constitutes the hall-tree or rack, and 2 the bed-frame, which is arranged to swing head down in the lower part 55 of said casing. The sides of the bed-frame at each end are raised, as shown, to conveniently hold the bed-bottom and bedding. To each side of the bed-frame at the head are secured the cam-blocks 3, which on their forward edges are curved eccentrically, and around said edges extend the supporting-chains 4, which are fastened at their lower ends to studs 5 at the sides of the bed-frame immediately in front of the smaller ends of 65 said cam-blocks. The upper ends of said chains are secured to similar studs 6 on the inside of the sides of the bed-casing 1 about midway between the top and bottom thereof. The inner sides of the casing at the lower 70 part thereof are also provided with the stationary cams or shoes 7, which are irregularly curved on their rear edges, as shown.

The head of the bed-frame at opposite sides is provided with rollers 8, which travel along 75 the curved edges of said stationary cams or shoes as the bed-frame is raised or lowered to guide and control its movement, as more fully hereinafter explained.

The rear of the bed-casing at its lower corners is provided with angular plates 9 to hold the head of the bed-frame in place when folded.

The pillow-board 10 is hinged to the edge of the head-board and provided with the 85 weights 11 to counterbalance said bed-frame as it is raised and lowered.

The bed-casing is formed with a forwardly-extended base, which constitutes a seat and serves to give the base sufficient breadth to 90 steady said bed-casing and the head of the bed-frame when down or unfolded.

The bed-frame near the foot is provided with the usual folding legs 12, which support said frame when down or unfolded. The front 95 of the bed-casing may be ornamented in any desired manner and is provided with the hooks 13, upon which various articles may be hung.

The operation of my invention is as follows: When the bed-frame is down or unfolded, the rollers 8 rest upon the curved portions of the cams or shoes 7, before mentioned. In raising the bed-frame these rollers travel

down the curved portions of said cams or 45
shoes, which guide said rollers and cause the
head of the bed-frame to fit securely between
said cams or shoes and the angular plates 9,
5 before mentioned, so as to securely hold the
bed-frame in an upright position. The cam-
blocks 3 and the supporting-chains 4 give the
bed-frame when raising the same a rapid
10 perpendicular movement after said frame
passes an angle of about forty-five degrees
and thus prevents the head-board from strik-
ing the floor.

Having thus fully described the peculiar
15 construction and arrangement or combination
of the several parts of my invention and its
advantages and operation, what I claim as
new is—

1. In a folding bed, the combination, with
20 the bed-casing or hall-tree, of the bed-frame
having eccentric cams thereon and support-
ing-chains passing thereover, said chains hav-
ing their opposite ends attached, respectively,
25 near the middle of said casing or hall-tree and
near the lower ends of the sides of said bed-
frame, substantially as described.

2. In a folding bed, the combination, with
20 the bed-casing or hall-tree, of the bed-frame
having cams thereon, supporting-chains pass-
ing over said cams, fastening-studs for the
upper and lower ends of said chains, said
30 chains having their opposite ends attached,
respectively, near the middle of said casing
or hall-tree and near the lower ends of the
sides of said bed-frame, cams or shoes having
35 irregularly-described rear faces, rollers on the
opposite sides of the head of said casing, and
the angular plates for holding the head of
said bed-frame, substantially as described.

3. In a folding bed, the combination, with
40 the bed-casing or hall-tree, of the bed-frame
having cams thereon, supporting-chains pass-
ing over said cams, fastening-studs for the
upper and lower ends of said chains, said
chains having their opposite ends attached,

respectively, near the middle of said casing 45
or hall-tree and near the lower ends of the
sides of said bed-frame, cams or shoes having
irregularly-described rear faces, rollers on the
opposite sides of the head of said casing, the
50 angular plates for holding the head of said
bed-frame, and the weighted pillow-board,
substantially as described.

4. In a folding bed, the combination, with
the bed-casing or hall-tree, of the bed-frame
having cams thereon, supporting-chains pass- 55
ing over said cams, fastening-studs for the
upper and lower ends of said chains, said
chains having their opposite ends attached,
respectively, near the middle of said casing
or hall-tree and near the lower ends of the 60
sides of said bed-frame, cams or shoes having
irregularly-described rear faces, rollers on the
opposite sides of the head of said casing, the
angular plates for holding the head of said
65 bed-frame, the weighted pillow-board, and the
folding legs upon said bed-frame, substan-
tially as described.

5. In a folding bed, the combination, with
the bed-casing or hall-tree, of the bed-frame
having cams thereon, supporting-chains pass- 70
ing over said cams, fastening-studs for the
upper and lower ends of said chains, said
chains having their opposite ends attached,
respectively, near the middle of said casing
or hall-tree and near the lower ends of the 75
sides of said bed-frame, cams or shoes having
irregularly-described rear faces, rollers on the
opposite sides of the head of said casing, the
angular plates for holding the head of said
80 bed-frame, the hinged and weighted pillow-
board, and the folding legs upon said bed-
frame, substantially as described.

In testimony whereof I affix my signature in
presence of two witnesses.

WILLIAM S. GUNN.
